BRUSH

Charles C. Gerhardt, Douglas Manor, Long
Island, N. Y.

Application September 13, 1932, Serial No. 632,875

8 Claims. (Cl. 15—183)

This invention relates to brushes, and particularly to rotary brushes such, for example, as rotary wire brushes intended for buffing, polishing or cleaning, and a general object of the invention is both to provide an improved brush from the standpoint of its efficiency in operation and, at the same time, to facilitate the making, assembling, disassembling and reconditioning of the brush.

10 The bristles of rotary brushes which are power driven for buffing or polishing or cleaning are comparatively short lived and when the work which is done by these brushes is comparatively heavy as, for example, in the case of rotary wire-bristle brushes for cleaning boiler tubes, the whole brush structure, including the body for holding the bristles, must be substantial, which adds considerably to the initial cost of the brush. It is desirable, therefore, that those brushes the 15 bristles of which are comparatively short lived, and particularly brushes which have an exceedingly heavy duty to perform, such as the cleaning of scale from water-tube boiler tubes, be so constructed that they can readily be reconditioned 20 instead of having to be thrown away when the bristles are worn out.

One of the objects of the present invention is so to improve brush constructions, and particularly the construction of rotary brushes, that 25 when the bristles have become worn or so distorted as seriously to affect the efficiency of the brush, the bristles may readily be replaced in the brush body.

Another object of the invention is so to improve the construction of rotary brushes, and particularly the bristle holding parts thereof, that as great a number of bristles as is conveniently possible may be firmly confined in the brush body.

40 Still another object of the invention is so to construct each tuft of bristles that it may readily be handled as a unit both in assembling it in the brush body and in removing it from the body for purposes of replacement.

45 Other objects and important features of the invention will appear from the following description and claims when considered in connection with the accompanying drawing in which—

50 Figure 1 is a longitudinal section on the line 1—1 of Figure 2 of a rotary brush embodying the present invention;

Figure 2 is a section on the line 2—2 of Fig. 1;

55 Figure 3 is a section on the line 3—3 of Fig. 4 through a tuft of bristles confined in a sleeve be-

fore the tuft and sleeve have been bent into their final form;

Figure 4 is a side elevation of the tuft and associated sleeve referred to in the description of Fig. 3;

Figure 5 shows the tuft of bristles bent to the form in which it is inserted in the brush body;

Figure 6 illustrates a modified form of tuft of such lateral dimensions that a single tuft will fill one of the slots in the brush body;

Figure 7 is an end view of the tuft shown in Fig. 6;

Figure 8 is a section on the line 8—8 of Fig. 1 illustrating the slotting of the brush body, and

Figure 9 shows a modified means for retaining the tufts of bristles in their proper operative relation to the brush body.

The invention is shown for illustrative purposes as embodied in a rotary brush having a metal body and wire bristles, but it will be understood that the invention in its broader aspects, is not confined to bodies or bristles of any particular shapes or materials and that the invention is of wide utility and applicability in the brush art.

In brushes for cleaning or polishing purposes it is usually important that the bristles be so arranged in the brush body that in their movement over the surface to be cleaned as many bristles as possible contact with each part of the surface to be cleaned. To this end it is desirable, therefore, that each row of bristles or of tufts of bristles be as continuous as is practically possible throughout the length of the brush proper. In the illustrative embodiment of the invention the bristles or tufts of bristles have been arranged side by side in slots extending substantially throughout the length of the brush body so that in the rotation of the brush each row of bristles will effect a brushing action that is substantially continuous throughout its entire length.

A convenient way of forming a brush body to receive substantially continuous rows of bristles or of tufts of bristles is that shown in the illustrative embodiment of the invention in which a cylindrical brush body 2, having an internally screw-threaded extension 4 to receive the driving mechanism, is transversely slotted in planes which include the axis of the cylinder, each of these slots being of sufficient width to receive a substantial tuft of bristles. Starting with a solid cylinder, the slotting of the cylinder, as shown, will form a hollow center in the brush body where the various slots 6 intersect. The partitions 8

formed by the slotting will be segmental or V-shaped in cross section, as shown.

In order to facilitate insertion and removal of the bristles and, furthermore, to insure their being closely confined and firmly held in the brush body, each tuft 10 of bristles is provided with a closely fitting sleeve 12 confining a portion of the tuft intermediate between its ends. This sleeve may be fitted to the tuft of bristles or the tuft of bristles may be fitted to the sleeve in various ways. A simple and convenient way of providing each tuft 10 with a sleeve 12 and of shaping the tuft into V form to fit over a segmental partition 8 is illustrated in the drawings where the tuft is shown as assembled first in a straight sleeve 12, of circular cross section, which is then bent at a point intermediate between its ends into substantially V form and at the same time flattened somewhat on opposite sides so that it will fit snugly and without turning in the slot 6.

If desired, instead of having a plurality of tufts, each provided with a sleeve, in each slot, a tuft may be formed, as shown in Fig. 6, which is wide enough to fill the entire slot and is correspondingly provided with a sleeve which extends throughout the length of the slot.

To retain the tufts in assembled position in the slots, a cap or end piece 14 is adapted to be clamped against the ends of the partition members 8 of the brush body, this cap or end member being preferably of the same diameter as the brush body 2 and having a flange which fits against shoulders 16 provided at the ends of the partition members 8.

To clamp the cap or end member 14 in tuft-retaining position against the shoulders 16 on the partitions 8, a bolt 18 is provided, which is preferably of such diameter that it serves as an abutment to prevent the tufts from being pushed inwardly toward the center of the brush, the bolt 18 being provided with a head 20 engaging either the cap 14 or a washer 22 located between the head 20 and the cap 14 and being threaded at its end to screw into threads tapped into the solid part of the brush body, thus permitting its convenient removal when it is desired to remove and replace the tufts to recondition the brush.

As an alternative method of clamping the cap 14 against the shoulders 16, a bolt 24 having a relatively thin head 26, tapered on its under side to fit the concavity at the bottom of the threaded socket in the extension 4 of the brush body, may have its shank or stem extended through the cap 14 and threaded to receive a nut 28 for clamping the cap 14 in position. This alternative construction avoids the necessity for having a substantial partition between the end of the threaded socket in the extension 4 and the interior of the brush body proper for the threads for holding the bolt 18, thus permitting the brush structure, as a whole, to be somewhat shortened.

What I claim as new is:

1. A rotary brush comprising a body having a hollow center and longitudinally-extending peripherally spaced bristle-receiving slots cut on radii from the axis of rotation, tufts of bristles each shaped to project through two slots and to embrace the partition separating said slots, each tuft being provided with a sleeve confining that portion of the bristles intermediate between the ends thereof and of a transverse dimension to fit snugly between the walls of the slots, said sleeve being bent sharply, whereby to produce a crimp therein which will securely grip the bristles against longitudinal movement.

2. A rotary brush comprising a cylindrical body transversely slotted in planes including the axis of the cylinder, tufts of bristles each shaped to project through two adjacent slots and to embrace the partition separating said slots, and means for confining said tufts against movement out of said slots, comprising a plate closing the open ends of said slots and an axially extending member serving both to maintain said bristles in projected relation to said cylindrical body and said plate in closing relation to said slots. 80

3. A bristle tuft construction for insertion into or removal from a brush body as a unit comprising a bundle of bristles and a tube or sleeve surrounding and confining said bristles throughout a portion of their extent intermediate between their ends, said tube or sleeve and the associated bristles being bent substantially to V shape whereby said tube or sleeve is crimped so as to form a crimp in the tube or sleeve, and thereby securely clamp the bristles therein. 90

4. The process of assembling tufts of bristles in substantially V shape for insertion into a brush body, which comprises inserting the bristles into a tube or sleeve of substantially circular cross section so that said sleeve surrounds and confines that portion of the bristles intermediate between the ends thereof and then forming a crimp in the tube or sleeve to securely clamp the bristles therein by bending said tube or sleeve 100 and the confined bristles into V shape. 105

5. The process of assembling tufts of bristles in substantially V shape for insertion into a brush body, which comprises inserting the bristles into a tube or sleeve of substantially circular cross section so that said sleeve surrounds and confines that portion of the bristles intermediate between the ends thereof and then forming a crimp in the tube or sleeve to securely clamp the bristles therein by bending said tube or sleeve and 110 the confined bristles into V shape and at the same time flattening the opposite sides of said tube. 115

6. A rotary brush comprising a longitudinally slotted cylindrical body having an open center 120 formed by intersection of the slots in the axis of the cylinder, tufts of bristles each bent to project through two adjacent slots and to embrace the partition separating said slots, each tuft of bristles being provided with a sleeve which is 125 also bent substantially to V shape to embrace said partition, which fits snugly between the walls of the two slots into which it projects, extends to a position substantially flush with the outer surface of the cylinder and confines that portion 130 of the bristles which is located between the exposed parts of the tuft, and means for maintaining the said bristles in projected relation to the cylindrical outer surface of the brush body comprising a member extending through the center 135 of said body and bearing against the bends of the bristle confining sleeves. 140

7. A brush including a cylindrical body, said body provided with transverse communicating slots, the portions of the body between the transverse slots being substantial sectors, wire bristles doubled upon themselves to provide a pair of tufts, and seated in the slots with one tuft projecting outwardly through each slot, and a cylindrical member thrust through the open center of said body provided by the communicating slots for holding said tufts in seated relation to said sectors. 145

8. A brush including a cylindrical body, said body provided with transverse communicating 150

slots, the portions of the body between the transverse slots being substantial sectors, wire bristles doubled upon themselves to provide pairs of angularly arranged tufts, said pairs of tufts being seated in the slots with the tufts of each pair extending outwardly through adjacent slots, and means secured to the end of the body portion for securing the bristles in place, and a cylindrical member thrust through the open center of said body provided by the communicating slots for holding said tufts in seated relation to said sectors.
